US0D1089658S

(12) **United States Design Patent** (10) **Patent No.:** **US D1,089,658 S**
(45) **Date of Patent:** **** Aug. 19, 2025**

(54) **OCULAR DEVICE**

- (71) Applicant: **ArcScan, Inc.**, Golden, CO (US)
(72) Inventors: **Johan Erik Giphart**, Aurora, CO (US); **Keir Hart**, Lafayette, CO (US); **Barry Schafer**, Folsum, CA (US); **Andrew K. Levien**, Morrison, CO (US)
(73) Assignee: **ArcScan, Inc.**, Golden, CO (US)
(**) Term: **15 Years**
(21) Appl. No.: **29/824,355**
(22) Filed: **Jan. 24, 2022**
(51) LOC (15) Cl. **24-02**
(52) U.S. Cl. **USPC D24/172**
(58) **Field of Classification Search**
USPC D24/170, 172, 185–187, 231, 232, 140, D24/158–160, 120, 184, 137; D15/199; D16/100, 130, 136, 200, 300
CPC A61B 3/02; A61B 3/0025; A61B 3/32; A61B 3/024; A61B 3/028; A61B 3/12; A61B 3/103; A61B 3/005; A61B 3/06; A61B 3/0008; A61B 3/063; A61B 3/113; A61B 3/0041; A61B 3/0091; A61B 5/7275; G06T 2207/30041; G02C 13/003; G02C 3/003

(57) **CLAIM**

The ornamental design for an ocular device as shown and described.

DESCRIPTION

FIG. 1 is a perspective view of an ocular device of the claimed design;

FIG. 2 is a front perspective view of the ocular device of FIG. 1;

FIG. 3 is a back perspective view of the ocular device of FIG. 1;

FIG. 4 is a front elevation view of the ocular device of FIG. 1;

FIG. 5 is a back elevation view of the ocular device of FIG. 1;

FIG. 6 is a right elevation view of the ocular device of FIG. 1;

FIG. 7 is a left elevation view of the ocular device of FIG. 1;

FIG. 8 is a top plan view of the ocular device of FIG. 1; and, FIG. 9 is a bottom plan view of the ocular device of FIG. 1. The broken lines in the figures depict portions of the ocular device that form no part of the claimed design. In FIG. 1, the additional broken lines illustrating a table and monitor depict environmental structure and form no part of the claimed design.

1 Claim, 9 Drawing Sheets
